UNITED STATES PATENT OFFICE.

GEORGE W. PERKS, OF AKRON, OHIO, ASSIGNOR, BY DIRECT AND MESNE ASSIGNMENTS, TO THE GEORGE W. PERKS COMPANY, OF AKRON, OHIO, A CORPORATION OF OHIO.

MOUNTING FOR ABRASIVE WHEELS.

Application filed December 8, 1925. Serial No. 73,998.

The invention relates to mountings for wheels used in grinding operations which rotate at a high rate of speed and aims to provide means which will prevent broken 5 parts from being thrown radially outward in the event of wheel breakage so as to lessen the hazard of persons in the vicinity of the wheel.

Heretofore it has been the practice to insert washers of comparatively soft material, such as rubber, leather, lead, blotting paper and the like between the wheel and the clamping collar or flange suitably secured to the revolving shaft forming the supporting spindle for the abrasive wheel.

The intended function of the washers of rubber, leather and the like formerly used was to prevent fragments of a broken abrasive wheel from being thrown outwardly by 20 centrifugal force, but they have been unsatisfactory in practical operation and have frequently caused either death or serious injury to operators or others in the vicinity of a bursting wheel.

25 My improved means for gripping the abrasive wheel exerts a more tenacious grip on the latter than the washers of yielding material heretofore used and suggested by certain patents in the prior art, and by actual test I have determined that where former holding means failed at a given rate of speed, my improved holding means do not so fail.

The characteristic features of my invention will be apparent from the following 35 specifications when read in connection with the accompanying drawings and points of novelty will be indicated with particularity in the appended claims.

40 In the drawings:

Figure 1 is a section illustrating an abrasive wheel firmly held in place by my improved mounting;

Figure 2 is an end elevation thereof;

45 Figure 3 is a magnified section illustrating the manner in which the comparatively rough surface of the abrasive wheel interlocks with the film of yielding material secured to my improved gripping member;

50 Figure 4 is a detailed face view of one of my gripping members;

55 Figures 5 and 6 are diagrams illustrating the advantage of a thin film of rubber over the comparatively thick washers heretofore used;

Figure 7 is a cross-section through an abrasive wheel of a somewhat different type showing the invention as applied thereto; and

Figure 8 is a side view of a clamping ring 60 used in the construction shown in Figure 7.

In these various figures, 10 is any suitable shaft, arranged to revolve an abrasive wheel 11. Shaft 10 has a collar 12 secured thereon in any usual manner in engagement 65 with a shoulder 13 on the shaft. The abrasive wheel 11 is clamped between clamping plates 14, 14 by means of a nut 10^a threaded on the end of shaft 10. Each of the clamping plates or flanges 14 is provided 70 with a circular recess or depression 15 below the plane of the flange at its outer diameter, thus providing a raised annular surface 16 which is pressed against the wheel over an area which may be predetermined.

75 The gripping members of the present invention are interposed between the flanges 14, 14 and the opposite sides of the abrasive wheel. They are indicated at 17, 17 and in the form shown each includes a stiff backing plate 18, preferably of metal, having securely vulcanized or otherwise intimately secured thereto a film 19 of tough, yielding rubber, such, for example, as tire tread stock.

80 By reference to Figure 3, it will appear that the projections 11^a on the sides of the abrasive wheel 11 engage in the rubber surfaces 19 of the members 17, 17 and that the rubber, under the pressure applied by tightening the clamping nut 10^a, will be imbedded into the depressions of the wheel 11, the members and wheel thus making an intimate contact with each other throughout the area of the annular surface 16 of flange 14. 95 It is evident, therefore, that should the abrasive wheel break in use, the centrifugal force exerted by the rapidly rotating fragments would be opposed by the grip exerted thereon by the rubber surfaces 19, 19, which, in turn, would transmit the opposing force to the metal discs 18, 18, which are made sufficiently heavy to withstand the centrifugal stresses with an ample factor of safety.

100 By an exhaustive series of experiments, I have found that a comparatively thick layer of rubber is less effective for the purposes of my invention than a layer approximately .010 inch in thickness; that due to the enormous adhesive strength of the rub- 110

ber when vulcanized to the disc, broken fragments of wheels may be revolved at speeds far in excess of the speed at which similar fragments will fly out when clamped between washers of rubber, blotting paper, or the like, heretofore proposed.

Referring to Figures 5 and 6, the former figure illustrates a comparatively thick washer such as suggested by the prior art, which experience has shown fails in practical operation. My theory of the cause of failure is that the long fibers indicated diagrammatically as f , provide a comparatively long moment arm, indicated by the dimension x . Centrifugal force acting in the direction indicated by the arrow P tends to flex the fibers as indicated. This flexing of the fibers reduces the thickness of the washer an amount, for example, as indicated at m (exaggerated) and thus loosens the hold between the flange and wheel and permits fragments to fly outward. In contradistinction, Figure 6 illustrates the gripping member of my invention, in which the film of rubber f^1 is of minute thickness, in practice ranging from between .005 to .020 in thickness. The moment arm x^1 is practically infinitesimal and there is no decrease in thickness as compared with the decrease marked at m in Figure 5 because the short fibers of the rubber film f^1 , being comparable to the interstices in the face of the wheel, are in firm interlocking engagement therewith. Furthermore, my film of rubber, being intimately bonded to the metallic disc 18, will transmit any outwardly acting forces exerted by broken fragments directly to the metal disc. It will be understood that the disc 18 will in turn transmit such force through its own body and through the clamping member 14 to the shaft 10 which is well capable of resisting the same. Hence, my improved holding member will prevent a fragment flying from the wheel where former expedients have failed. Stated in another way, the gripping member embodied in my invention provided with an extremely thin film of rubber or the like intimately bonded thereto is capable of exerting a much more tenacious grip on the abrasive wheel than arrangements heretofore proposed.

In the form of the invention illustrated in Figures 7 and 8, the abrasive wheel is indicated by the numeral 20, being provided about its inner circumference with a rib 21. The shaft is indicated at 22 and its provided with a flange 23 permanently secured thereto. The wheel is clamped in position between the flange 23 and a removable flange 24, the parts being tightened by bolts 25. In this form of the invention, the discs are substantially ring shaped, as indicated at 26, and are provided with the facing of rubber 27 as in the other form of the invention. It will be noted that there is no fit between the

disc and the shaft in this form of the invention, the centrifugal stresses being transmitted to the shaft through the flange 23.

The thickness of the layer or film may be varied within narrow limits as indicated. The thickness of the rubber is comparable to the average depth of the minute interstices in the face of the grinding wheel so that when the pressure is applied, the high points upon the wheel project into the yielding surface of the rubber until they substantially contact the backing member. In this way the small areas of rubber are substantially isolated one from the other and no opportunity is afforded for the rubber to creep or work under centrifugal force, and the only way that a fragment can fly out is by tearing the rubber from the disc as has been proven by actual demonstration. The intimate bonding of the rubber film and the disc prevents this action. The surface of the rubber facing is preferably smooth so that the gripping action will be continuous throughout the extent of the contact between the disc and clamping plate.

It will also be noted that the formation of the comparatively narrow annular surfaces 16 about the outer peripheries of the clamping members 14 concentrates the force which is applied by securing the discs together through tightening of the nut 10^a, over relatively narrow bands spaced from the center of the grinding wheel, the location of which depends upon the diameter of the flanges 14. In this manner the clamping action is concentrated on the outer periphery of the discs and should breakage occur, the ability to retain the broken fragments will be far superior to a construction in which the clamping force is distributed throughout the entire area of the disc or near its axis.

It will also be noted that the rubber facings on the disc have sufficient cushioning properties to compensate for irregularities in the surfaces of the wheel, so that no excessive clamping strain can be applied which otherwise would subject the wheel to strains which might cause its fracture when in service or in mounting. As an additional advantage the rubber facing upon the disk will recover its normal condition when the clamping strain is relieved and may be used repeatedly and for clamping wheels of various grains.

It is not necessary to have a close fit between the disc and the shaft, the hole within the center of the disc being of any desired diameter, as shown, for example, in Figures 7 and 8.

While I have described quite specifically a mounting for abrasive wheels including a gripping member having a thin film of rubber vulcanized thereto, it is to be understood that I may secure the film of rubber to the disc or backing by any suitable means.

so that the rubber is intimately bonded to the disc. Should other materials than rubber be found to possess suitable properties, I am at liberty to substitute such materials within the scope of the invention. It will also be understood that the principles of the invention may be applied to the clamping of other objects than abrasive wheels, which have surfaces with minute irregularities.

While I have described quite specifically the embodiment of the invention herein illustrated, it is not to be construed that I am limited thereto, as various modifications and substitution of equivalents may be made by those skilled in the art without departure from the invention as defined in the appended claims.

What I claim is:

1. A mounting for abrasive wheels including a rotary shaft and means for clamping the wheel to said shaft including a pair of clamping elements each having relatively stiff gripping members with a film of yielding, tough rubber vulcanized thereon, the thickness of the film being comparable to the depth of the interstices of the surface of the wheel.

2. A gripping element for use in mounting abrasive wheels having a rubber film forming part thereof of a thickness comparable with the coarseness of the surface of the wheel.

3. A gripping element for use in mounting abrasive wheels, said element including a stiff backing member having secured thereto a film of yielding, tough rubber of a thickness substantially .005 to .020.

4. An abrasive wheel mounting comprising a shaft, an abrasive wheel upon the shaft, a metallic member, a layer of rubber permanently secured and bonded to the member adjacent to the wheel, and means

to exert pressure upon said member to force the wheel and the layer of rubber together, the said layer being of such thickness that when pressure is applied, the high points upon the wheel will substantially contact the face of the member. 45

5. An abrasive wheel mounting comprising a shaft, an abrasive wheel upon the shaft, a metallic member, a layer of rubber permanently secured and bonded to the member adjacent to the wheel, and means to exert pressure upon said member about a narrow band located near the periphery of the member to force the wheel and the layer of rubber together, the said layer being of such thickness that when pressure is applied, the high points upon the wheel will 60 substantially contact the face of the member. 55

6. A device of the character described comprising rigid discs, a shaft, an abrasive wheel upon the shaft, means to exert clamping pressure upon said discs over narrow bands located near the periphery of the discs, and a thin film of yielding material permanently united to each disc adjacent to the wheel, the films of material gripping the rough faces of the wheel and transmitting the centrifugal stresses due to rapid rotation of the wheel directly to the discs and thence to the shaft. 70

7. A device for clamping an object having minute irregularities in a surface comprising a rigid disk, a layer of rubber intimately bonded to said disk, the thickness of the rubber being commensurate with the depth of said irregularities, and means for clamping the disk and the object together with the layer of rubber in contact with the irregular surface of the object so that the high points in the surface of the object will substantially contact with the face of the disk. 75 80
